UNITED STATES PATENT OFFICE.

RICKARD STRINDBERG, OF NEW YORK, N. Y., ASSIGNOR OF ONE-THIRD TO JOHN L. LOTSCH, OF BROOKLYN, NEW YORK.

INTERNAL-COMBUSTION ENGINE.

Application filed April 19, 1920. Serial No. 374,991.

My invention has for its object the production of a new and improved type of internal combustion engine.

The invention relates to internal combustion engines in which the air for supporting combustion is given a preliminary compression before being admitted to the cylinders, and has for its objects to provide an engine having a longer and more effective power stroke than those at present in use; wherein the pressure of the exhaust gases against the upward movement of the piston is reduced; wherein the danger of back firing is eliminated; which will be noiseless in operation; wherein the muffler may be eliminated; in which artificial cooling may be dispensed with; in which the gas mixture will be substantially free of products of combustion; which will be cheap to manufacture and economical of operation.

A further object of the invention is the production of a device, of the character herein described, which is extremely simple in construction, thoroughly reliable and efficient in its purpose, and which will not get easily out of order.

With these and other objects in view to be more fully set forth hereinafter, the invention consists in the novel construction, combination of elements, and arrangement of parts which will be exemplified in the construction hereinafter described in the specification and illustrated in the accompanying drawings considered together or separately.

The inventive idea involved is capable of receiving a variety of mechanical expressions, one of which for the purpose of illustrating the invention, is shown in the accompanying drawings.

The invention will be first described in connection with the accompanying drawings, wherein similar reference characters are used to designate corresponding parts throughout the several views, and then more specifically defined and indicated in the appended claims.

In the drawings,

Fig. 1 is a horizontal sectional view of an internal combustion unit embodying my invention, the section being taken on the line 1-1 of Fig. 3;

Fig. 2 is a similar view taken on the line 2-2 of Fig. 3;

Fig. 3 is a longitudinal section taken on the line 3-3 of Fig. 1;

Fig. 4 is a transverse section taken on the line 4-4 of Fig. 3;

Fig. 5 is a detail sectional view taken on the line 5-5 of Fig. 3;

Fig. 6 is a diagrammatic sectional view illustrating the operation of the device; and

Fig. 7 is a diagram showing all cycles during two revolutions of the engine shaft.

In carrying out my invention a unit comprising two cylinders A and B is employed. The cylinders are preferably cast en bloc, but it is to be understood that they may be cast single if desired.

In the cylinder A is carried a piston 1 preferably of the ordinary barrel type, and said piston is connected by means of a connecting rod 2 with a crank 3 on a shaft 4. The cylinder A is provided with an inlet valve 7 and an exhaust valve 8 as is common. These valves may be operated from the crank shaft 4 in the well known manner. In the side wall of the cylinder A is a port 9 which is in communication with the cylinder B.

The cylinder B carries a piston 10 connected to a crank 11 on the shaft 4 by means of a connecting rod 12. The piston 10 is provided with a port 13 adapted to cooperate with the lower end 14 of a duct 15 in the wall of the cylinder. The upper end of the duct communicates, as at 16, with the interior of the cylinder B at a point some distance above the opening 14. The cylinder B is likewise provided with an exhaust port 17 in communication with the atmosphere. The port 17 is below the level of the opening 16 whereby the latter will be disclosed before the former on the down stroke of the piston 10, and the port 17 will be closed before the opening 16 on the upstroke of the piston.

A passage 18 connects the cylinder B with the port 9 of the cylinder A, and a branch 19 connects the said passage and port with the upper end of the cylinder B. The head of the piston 10 is provided with a deflector 20.

The cylinders are supported on a tight crank casing 21, as in the ordinary two cycle engine, and the casing is provided with an air inlet valve 22 of any desired type, and one of the cylinders is provided with an ignition device (not shown) of any preferred construction.

The crank 3 has a 90° angular advance over the crank 11, and while a single unit

of two cylinders is illustrated, it is to be understood that any number of units may be employed with the cranks of the various units so arranged relatively to each other that vibrations will be largely if not entirely eliminated.

While water jackets or other cooling devices, and a muffler, are not necessary to the operation of the device of the application, those devices may be employed if desired without departing from the spirit or scope of the invention.

In Fig. 6 the cranks 3 and 11 are illustrated as at right angles to the positions they actually occupy, as are the port 18 and duct 15.

The operation is as follows, attention being specially directed to Figs. 6 and 7.

Assuming the piston 1 is at the upper dead point *a* with the inlet valve 7 and exhaust valve 8 closed and a charge is exploded in the cylinder A:—

Piston 10 will be at *a'*, and the upper part of cylinder B will be open through branch 19, port 9 and the lower part of cylinder 1 to the casing 21, so there will be no compression in the upper part of cylinder B. Exhaust 17 and shunt 15 will be closed.

Because of the impulse of the exploding charge, piston 1 will move down to point *b* while piston 10 is moving up to point *b'*. In this position, port 9 will be closed, port 18 closed and exhaust 17 closed.

The continuing effect of the exploding charge will cause piston 1 to move down to point *c* while piston 10 is moving to its upper dead point *c'*. In this position, port 9 will be closed but port 18 partly open to the casing 21 and exhaust 17, whereby pressure above the piston 10 and branch 19 will be released.

Continuing effect of the exploding charge will cause piston 1 to move down to position *d* while piston 10 moves down to position *d'*. As piston 1 passes point *i*, port 9 starts to open and pressure of gas in cylinder A is transferred via port 9 and branch 19 above the head of piston 10, impelling said piston downward.

Continuing its downward movement, piston 1 travels the relatively small distance from *d* to *e* (its lower dead point) while piston 10 is traveling the relatively great distance down from *d'* to *e'*, thus providing a relatively large expansion space above the piston 10 and drawing part of the products of combustion out of cylinder A through port 9 and branch 19. At this point, port 18 and exhaust 17 are closed.

Beginning its upward stroke, piston 1 goes up to *f* while piston 10 moves down to *f'*. In this position, port 9 is open, port 18 is open and branch 19 is open through the upper part of cylinder B to the exhaust 17 with the result that practically all the re-

maining products of combustion are exhausted through 17.

Continuing its upward stroke, piston 1 goes up to *g* while piston 10 is going to its lower dead point *g'*. In this position, port 9 is closed, interrupting communication between the cylinders, port 18 is open, branch 19 is open, exhaust 17 is open to the upper part of cylinder B, and by means of port 13 and ports 14 and 15 and channel 16, the casing 21 is in communication with exhaust 17 and atmospheric pressure prevails throughout cylinder B.

Continuing its upward stroke, piston 1 goes to position *h* while piston 10 goes up to position *h'*. In this position, port 9 is closed, port 18 is partly open, passage 19 is open, exhaust 17 is partly open, so that no pressure is created in cylinder B by upward movement of piston 10.

Continuing its upward movement, piston 1 goes to its upper dead point *a*, while piston 10 is going upward to point *a'*. In this position pressure on the upper part of cylinder A is relieved through valve 8, and pressure in the upper part of cylinder B is relieved through branch 19, port 9, the lower part of cylinder A, and the casing 21.

Beginning the suction stroke, piston 1 moves down to *b* while piston 10 is moving up to position *b'*. In this position, port 9 is closed, port 18 is closed, exhaust 17 is closed, port 16 is closed with the result that air is compressed in the upper part of cylinder B and branch 19.

Continuing the suction stroke, piston 1 moves down to position *c* while piston 10 moves up to its upper dead point *c'*. In this position, port 9 is closed, port 18 is partly open and exhaust 17 is open, relieving the pressure in the space above piston 10 and restoring atmospheric pressure throughout cylinder B.

Continuing its suction stroke, piston 1 goes down to its lower dead point *e* while piston 10 is traveling downward from *C'* to *e'*. Through a small part of this stroke (from *i* to *e*), the port 9 is open, port 18 closed and passage 19 open so that some suction will be created in the upper part of cylinder B, and while some loss of gas from cylinder A will occur, this, due to the relatively much larger volume of the upper part of cylinder A at this part of the stroke, will be slight.

Starting its compression stroke, piston 1 will go to position *g* while piston 10 is going to its lower dead point *g'*. In this position, port 9 is closed, port 18 is open, exhaust 17 is open, ports 14 and 16 connecting the upper part of cylinder B with the casing 21 by passage 15 are open so atmospheric pressure is restored throughout the casing and cylinder B.

Continuing its compression stroke, piston

1 goes up to position α while piston 10 goes up to position α' , thus completing a two revolution cycle.

It will be noted that the expanding gas from the explosion in cylinder 1 is permitted to exhaust by expanding in cylinder B and expend its force against piston 10, which is propelled by the force of said gas, thus increasing the volume of the cylinder B above piston 10. The momentum of the expanding gas is, therefore, reduced by performing useful work in moving the piston and thus assisting in the propulsion of the shaft 4 and its momentum is so reduced that when it passes out of exhaust 17 its speed will be so reduced that no muffler is necessary. It will also be apparent from the cycle of operation described in detail above that at no time is there any considerable back pressure retarding the movement of piston 10 and thus cutting down the power of the motor.

As shown in Fig. 7 the expansion in cylinder A occurs during 140° of a cycle, and the working stroke of cylinder B begins at the end of the working stroke of cylinder A and extends over 90° of the cycle. The combined working stroke is therefore 230° .

As the products of combustion leave the cylinder A they expand into cylinder B and thence into the atmosphere through the port 17. There will, therefore, be practically no resistance when the piston 1 begins its upward movement. This is directly the reverse of conditions in the ordinary four cycle engine. The expansion of the gases of combustion from cylinder A to cylinder B just above described will obviate the necessity for a muffler and its resistance of from 10 to 20% is eliminated.

As most of the hot gases of combustion are exhausted through port 17 which is open to the atmosphere, those gases exhausting through the valve 8 will be of comparatively low temperature and the danger from back firing caused by hot exhaust pipes is minimized.

The continual reduction in pressure of the gases from the time of the explosion in cylinder A until the exhaust port 17 will lower the pressure to such an extent that the gases will exhaust without noise and at such a low temperature that a muffler will not be necessary.

The clearance between the head of the cylinder B and the head of the piston 10, when at its upper dead point, is preferably made relatively small, so that during those parts of the suction and compression strokes of the piston 1 that the port 9 is open, the entry of fuel gas from cylinder A will be minimized.

In accordance with the provisions of the patent statutes, I have described the principle of my invention together with the apparatus which I now consider to repre-

sent the best embodiment thereof, but I desire it understood that my invention is not confined to the particular form of apparatus herein shown and described, the same being merely illustrative, and that the invention can be carried out in other ways without departing from the spirit of my invention, and, therefore, I claim broadly the right to employ all equivalent instrumentalities coming within the scope of the appended claims, and by means of which objects of my invention are attained, and the new results accomplished, as herein set forth, as it is obvious that the particular embodiment herein shown and described is only one of many that can be employed to attain these objects and accomplish these results.

Having now described the invention what is claimed and desired to be secured by Letters Patent is:

1. In an internal combustion engine, a first cylinder and a second cylinder, a port connecting mid sections of said cylinders, a continuously open branch extending from said port to the upper end of the first of said cylinders, and pistons in said cylinders, the piston in said second cylinder forming a slide valve for said port and having a lead over the piston in said first cylinder sufficient to uncover said port as the piston in said first cylinder approaches the top of its stroke, whereby pressure is relieved above the piston in said first cylinder.

2. In an internal combustion engine, an explosion cylinder and an expansion cylinder, each opening at its lower extremity into a common casing, a port connecting the mid sections of said cylinders, a branch extending from said port to the upper end of the expansion cylinder, an exhaust port in said expansion cylinder substantially aligned with said cylinder connecting port, a fluid shunt opening into said expansion cylinder at a point substantially above and at a point substantially below said exhaust port, pistons in said cylinders each adapted to form a closure for said cylinder connecting port, said pistons being of such a length as to uncover said cylinder connecting port at both extremities of their stroke, and intake and exhaust ports in the upper end of the explosion cylinder.

3. In an internal combustion engine, an explosion cylinder and an expansion cylinder, each opening at its lower extremity into a common casing, a port connecting the mid sections of said cylinders, a branch extending from said port to the upper end of the expansion cylinder, an exhaust port in said expansion cylinder substantially aligned with said cylinder connecting port, a fluid shunt opening into said expansion cylinder at a point substantially above and at a point substantially below said exhaust

port, pistons in said cylinders each adapted to form a closure for said cylinder connecting port and the piston of said expansion cylinder being also adapted to form a closure for said exhaust port and for both ends of said shunt, and having a port adapted to be alined with the mouths of said shunt; said pistons being of such a length as to uncover said cylinder connecting port at both extremities of their stroke, and intake and exhaust valves at the upper end of said explosion cylinder.

4. In an internal combustion engine, a first cylinder and a second cylinder, a port

connecting said cylinders at their mid portion, a continuously open branch extending from said port to the upper end of said first cylinder, a piston in said second cylinder adapted to form a sliding closure for said port and to uncover the same both at the upper and lower ends of its stroke, whereby an intake passage and a pressure relief passage is alternately provided from the upper end of said first cylinder through said port to said second cylinder.

This specification signed this 3rd day of April, 1920.

RICKARD STRINDBERG.
